(57) CLAIM

I claim the ornamental design for a bahama awning hurricane shutter, as shown and described.

DESCRIPTION

This application claims the benefit of the filing date of non-provisional U.S. application Ser. No. 11/879,930, filed Jul. 19, 2007, the entire disclosure of which is expressly incorporated by reference herein.

FIG. 1 is a front, right, perspective view of a bahama awning hurricane shutter showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a front, right, perspective view with the louvers in a closed position.

Structural features shown in phantom lines are for illustrative purposes only and do not constitute a part of the claimed design.
